DRIVING-BELT.

1,205,363.

Specification of Letters Patent. Patented Nov. 21, 1916.

Application filed December 11, 1912. Serial No. 736,092.

To all whom it may concern:

Be it known that I, MAURICE LEBLANC, a citizen of the Republic of France, residing in Val Sur Seine par Croisy, (Seine et Oise,) France, have invented certain new and useful Improvements in Driving-Belts, of which the following is a specification.

This invention relates to a new type of driving belt made of vegetable or animal fibers, and comprises a foundation formed of parallel threads placed side by side and glued to one or two bands of thin cloth, the whole being covered by a protective fabric of a knitted kind which is first dressed and then glued to the said cloth. The protective fabric should be wider than the layer of threads to avoid damage of the belt when this is used under conditions which subject it to lateral wear, and the fabric should be reinforced by being thickened at the edges so as to be better able to resist the destructive action of the belt fork.

The following description with reference to the accompanying drawing will serve to explain the invention.

Figure 1 is a transverse section through a driving belt, in which there are two bands of cloth. Fig. 2 shows a modification of Fig. 1. Figs. 3 and 4 are diagrammatic elevations 30 of two forms of apparatus suitable for manufacture of the belt.

The belt consists of a layer of threads *a*, placed side by side and parallel to each other, the layer being glued to an upper 35 band and a lower band *b* of thin cloth in order that the layer of threads may have sufficient resistance in the transverse direction. The whole constitutes a band of high resistance in the longitudinal direction and 40 having sufficient coherence in the lateral direction. The purpose of this layer of threads is to give the belt the desired resistance to traction. Since the threads subjected to the pull are straight and all under 45 equal tension, they operate simultaneously and as they are embedded in gelatin or some other suitable agglutinant, the elongation which they suffer under the tension required of the belt is a real elongation of the fiber 50 of which they consist, so that the belts of which the threads form a part are not subjected to any preliminary elongation, as is the case with cloth belts which are required to resist traction and wherein the sinusoidal 55 curves formed by the chain threads must

be rectified before the threads themselves are stretched. The band of high resistance thus formed is covered by a protective fabric *c* analogous to that produced by lace making machines, or rather by knitting machines. This fabric is dressed, glued to the band and subsequently covered by a waterproofing coating. This fabric protects the band from damp and from wear by friction; it also gives the belt the best possible 65 adhesion.

An important function of a fabric having a warp is that it allows the use of the fasteners usually used for connecting together the ends of a driving belt. For this 70 purpose the warp should be sufficiently strong, for it will have to support the shearing action produced by nearly all types of fasteners which do not act by pressure.

It has already been stated that the protective fabric should have high resistance to friction and in particular the friction due to the belt fork, and for this purpose the invention provides a fabric, slightly 75 wider than the band of parallel threads, 80 and thick portions *d* consisting of pads of fabric, as shown in Figs. 1 and 2.

In the following there are described by way of example two processes for manufacturing belts according to this invention, 85 either in long lengths which can be cut up into belts of the desired length, or in the form of endless belts of an exactly pre-determined length suitable for the driving.

The chief advantages presented by the 90 belts made according to the invention are as follows:—1. That they have the property which has been improperly called inextensibility, and is in reality the property of remaining stretched on the pulleys without 95 the necessity for shortening the belts several times, as is the case with leather belts and woven belts. 2. That they have little thickness owing to the fact that they consist of only a single layer of threads contained between two layers of fabric. 3. They are light in comparison with their 100 resistance to traction, so that they can travel at high linear speeds, namely up to 70—80 meters per second. 4. They are supple owing to the fact that there is only a single layer of rectilinear threads, while the protective fabric, being woven, possesses a power of elongation much higher than that of the intermediate layer and only opposes 110

the smaller curvatures of the belt when these become exaggerated and would entail breakage.

No belt manufactured hitherto displays the characteristics which are obtained principally by the adoption of a single layer of threads, thus permitting the utilization of powerful agglutinants, such as gelatin, which do not impart stiffness, both for the layer itself and for the protective covering. A knitted fabric is more especially suitable for this protective covering, because such fabric does not possess threads comparable with the chain threads of a woven belt, and in consequence wear due to friction and particularly the wear produced by the belt fork, does not give rise to fraying, as in the case of woven belts. The covering fabric may have a warp so that the belt may be made without the cloth band already described, and the threads of this warp are connected by meshes of knitting which prevent the belt from breaking.

Fig. 3 represents two drums A, B, facing each other on which is wound a thread of resistance suitable for the force which the belt has to transmit. It is obvious that the thread may be wound on the drums through a number of turns as may be necessary, a comb K movable transversely being used to prevent the thread from crossing itself. A constant tension is given to the thread by any suitable means, such as by a weight P on a small pulley. When there is a number of turns suitable for the width of the belt desired, the several turns are pushed close to each other by hand and they are covered with a solution of glue or other suitable agglutinant. If a cloth band is used this is now glued to the layer of threads on one or both faces thereof. When the band is to be applied to both faces it is convenient to use a band of a little more than twice the width of the layer of threads and to apply it so that it extends equally beyond the sides of the layer and is then folded over the layer, its overlapping edge being glued so that the layer of threads is entirely surrounded by the band. The protective fabric which has already been dressed is now glued to the two faces of the band. The fabric is dressed and the sticking operations already described are performed with different agglutinants; for instance the threads are glued with gelatin and the knitted protective fabric is coated with caoutchouc. The whole is now allowed to dry and may then be cut up to form belts of desired lengths.

If the distance between the drums A and B is such as to produce a belt of a desired length, the belt can be made without being cut. In this case since the protective fabric will be supplied in the form of very long bands, they may be cut to the desired length and the ends connected together by carefully

splicing, so that the excessive thickness of the junctions may be negligible.

When long lengths are to be made to be subsequently cut up into the desired lengths, the gluing operation may advantageously be performed in two stages. The layer of threads glued to a cloth band or not may be allowed to dry and wound upon a drum. When a band of cloth is not used, this operation is only possible if the agglutinant has sufficient resistance, as is the case with caoutchouc or glue. Then, as shown in Fig. 4, the drum g, carrying the layer of threads, is mounted between two other drums f, h, each carrying a band of protective fabric previously dressed; the three bands are now unrolled from their respective rollers, passed through an opening i where they are brought together, and finally into a vat k containing hot glue. Long lengths may thus be glued very easily. Ejectors for throwing on the glue can further be provided before the slot i between the bands of protective fabric and the band of parallel threads.

For producing the knitted protective fabric, the frames known in the trade as Rachel frames may be used. These frames comprise principally two bars each carrying a row of needles which are caused to rise and descend alternately one after the other, while the threads are conducted and turned around the needles by heddle hooks mounted on the bars and operated by a suitable movement. These frames permit of a warp thread being introduced in the knitting. It is placed between the needles and the threads before the latter wind themselves around the needles and when the needles descend to make the mesh the warp thread is taken in.

Generally the frame will be operated with a single row of needles so that the fabric may have little thickness; it suffices therefore to suppress the needles of the other row. However, in certain cases of belts which have to work under very unfavorable conditions the knitting may be used which is made on both rows of needles, that is to say presenting two rows of mesh in the thickness; such a fabric may be provided with one or two warp threads for the double row of meshes. Generally the layer of parallel threads is glued between two knitted fabrics as aforesaid, and care is taken that the layer of glue should be as thin as possible so as not to make the belt stiff.

To protect the edges on the belt against the destructive action of the belt fork or any other source of friction, if knitted bands made upon a single row of needles and therefore having only a single thickness of mesh are used, there may be applied as already stated to each side of the band pro-

tective pads of the thickness of one or several meshes, which are produced by knitting these sides on both rows of needles. These edges will therefore have a double thickness 5 of mesh and may be made with coarser threads. It will also be apparent to those skilled in the art that these edges may have placed in them longitudinal threads which are not meshed but are simply surrounded 10 by the mass of the fabric for the purpose of imparting a certain stiffness to these protective edges. When the fabric is to have a double row of meshes the edges can be reinforced by using for making them coarser 15 and more compact threads than those used for the middle part of the band. With frames specially constructed for this purpose the warped fabric could be formed directly around the layer of parallel threads 20 which would be stretched between the two rows of needles, so that this layer would be surrounded by a sheath of knitting, closed on each side by threads worked on both rows of needles, while the threads supporting 25 the threads in the middle part would be worked on only one row. In this case the

protective border would be made by using for the operation stronger threads than in the middle part. In this case also the gluing should be done at the same time as the 30 manufacture of the sheath, allowing the hot glue to run along the layer of threads on its two faces between the rows of needles.

Having thus described my invention and the best means we know of carrying the 35 same into practical effect, I claim:—

An inextensible transmission belt comprising a single layer of threads of fiber, the threads being laid closely together side by side in contact with one another, said 40 layer of threads forming the body, and the tensile member, of the belt, a layer of fabric to which said threads are fastened to retain them in position, and a surface layer 45 of knitted fabrics.

In witness whereof, I have hereunto signed my name in the presence of two subscribing witnesses.

MAURICE LEBLANC.
